US00D812457S

(12) **United States Design Patent** (10) **Patent No.:** **US D812,457 S**
West (45) **Date of Patent:** **** Mar. 13, 2018**

(54) **COUPLING**

(71) Applicant: **SolarCity Corporation**, San Mateo, CA (US)

(72) Inventor: **Jack Raymond West**, San Rafael, CA (US)

(73) Assignee: **SOLARCITY CORPORATION**, San Mateo, CA (US)

(**) Term: **14 Years**

(21) Appl. No.: **29/525,418**

(22) Filed: **Apr. 29, 2015**

Related U.S. Application Data

(63) Continuation of application No. 13/402,846, filed on Feb. 22, 2012, now abandoned, which is a continuation-in-part of application No. 12/830,249, filed on Jul. 2, 2010, now Pat. No. 8,919,052, said application No. 29/525,418 is a continuation of application No. 14/504,168, filed on Oct. 1, 2014, now Pat. No. 9,599,280, which is a continuation of application No. 13/402,846, filed on Feb. 22, 2012, now abandoned, which is a continuation-in-part of application No. 12/830,249, filed on Jul. 2, 2010, now Pat. No. 8,919,052, said application No. 29/525,418 is a continuation of application No. 14/454,474, filed on Aug. 7, 2014, now Pat. No. 9,518,596, which is a continuation-in-part of application No. 12/830,249, filed on Jul. 2, 2010, now Pat. No. 8,919,052, said application No. 29/525,418 is a continuation of (Continued)

CLAIM

The ornamental design for a coupling, as shown and described.

DESCRIPTION

FIG. 1 is a top rear perspective view of a coupling showing the claimed design; and,

FIG. 2 is a right side view thereof.

The broken lines in the drawings illustrate portions of the coupling that form no part of the claimed design.

Portions of the coupling not shown in the figures form no part of the claimed design.

1 Claim, 1 Drawing Sheet

Related U.S. Application Data

application No. 14/531,155, filed on Nov. 3, 2014, which is a continuation of application No. 12/830,249, filed on Jul. 2, 2010, now Pat. No. 8,919,052.
